UNITED STATES PATENT OFFICE.

DANIEL THOMAS WILLIAMS, OF CRAIG, GEORGIA.

TELLURIAN.

SPECIFICATION forming part of Letters Patent No. 621,007, dated March 14, 1899.

Application filed April 6, 1898. Serial No. 676,645. (No model.)

To all whom it may concern:

Be it known that I, DANIEL THOMAS WILLIAMS, a citizen of the United States, residing at Craig, in the county of Gwinnett and State 5 of Georgia, have invented certain new and useful Improvements in Tellurians, of which the following is a full and complete specification, such as will enable those skilled in the art to which it appertains to make and use the 10 same.

This invention relates to tellurians; and the object thereof is to provide an improved device of this class which is simple in construction and operation and by means of 15 which the movement of the earth around the sun and the production and rotation of the seasons may be easily illustrated.

The invention is fully disclosed in the following specification, of which the accompanying drawings form a part, in which—

Figure 1 is a side elevation of my improved tellurian; Fig. 2, a partial plan view thereof; Fig. 3, a central vertical section of the base of the tellurian or the operative parts thereof. 25 Fig. 4 is a plan view of the construction shown in Fig. 3. Fig. 5 is a view similar to Fig. 4 with parts of the operative mechanism removed. Fig. 6 is a plan view of a part of the construction shown in Fig. 3. Fig. 7 is a plan 30 view of the disk which also forms a part of the operative mechanism shown in Fig. 3. Fig. 8 is a plan view of an oblong plate and a vertical tube connected therewith which forms a part of said mechanism. Fig. 9 is a 35 side view of a disk shown in Fig. 7 and a curved arm connected therewith. Fig. 10 is a partial section on the line 10 10 of Fig. 1. Fig. 11 is a side view thereof, and Fig. 12 is a plan view of one of the disks shown in Figs. 40 1 and 11 detached and provided with a ring which is secured to the perimeter thereof.

In the drawings forming part of this specification the separate parts of my improvement are designated by the same letters of reference in each of the views, and in the practice 45 of my invention I provide a device for the purpose herein specified which comprises a base-plate A, having upwardly and outwardly curved supports a, with the upper ends of 50 which are connected an annular plate C, the upper surface of which is divided into twelve

equal spaces C², on which in practice the signs of the zodiac are placed.

Secured centrally of the upper surface of the base-plate A is an elliptical casing a², provided at its base with outwardly-directed projections a³, by means of which connection with the base-plate A is made, and the elliptical casing a² is provided with a countersunk top a⁴, around the perimeter of which is an 55 annular groove a⁵, in which are placed ball-bearings a⁶, and said countersunk top a⁴ is provided centrally with a transverse elliptical opening a⁷.

Within the elliptical casing a² is placed an 60 oblong shaft-plate B, a plan view of which is given in Fig. 6, to which is secured a vertical shaft b, and said shaft-plate B is provided with transverse grooves b², arranged on opposite sides of and at equal distance from the 65 center thereof, in which are placed ball-bearings b³, and the ends of said plate are curved upwardly and inwardly to form inwardly-directed flanges b⁴, which extend inwardly even with the transverse grooves b². I also provide a vertical and movable tube D, which is provided at its lower end with an oblong base-plate d, a plan view of which is given in Fig. 8, and this plate d rests upon the ball-bearings b³, and the tube D projects upwardly 70 through the central transverse elliptical opening a⁷ in the countersunk top a⁴ of the elliptical casing a², and said base-plate d is also provided near each end with a transverse groove d², in each of which are placed ball- 75 bearings d³.

The inwardly-directed flanges b⁴ of the base-plate B overlap the ends of the base-plate d of the tube D and extend inwardly over the ball-bearings d³, the construction and arrangement of these parts being clearly shown 80 in Fig. 3, and said tube D and its base-plate d are free to move transversely of the base-plate B to which the shaft b is secured, and mounted on the countersunk top of the elliptical casing a² is a circular disk E, which is provided with an eccentric circular opening E², through which the tube D passes, and formed in one side of said disk E, eccentrically thereof, is a transverse cavity E³, in which 85 is secured a curved metal arm E⁴. Mounted 90 on the upper end of the shaft b, which pro-

jects above the annular plate C, is a globe or other device F, which represents the sun, and mounted on the upper end of the tube D is a revoluble band G, provided with an arm g, 5 the outer end of which is provided with an upwardly-directed extension g^2 , which projects above the annular plate C and is provided at its upper end with a horizontal outwardly-directed extension g^3 , and formed on 10 or secured to the lower side of the arm g are two keepers g^4 , through which the free end of the arm E⁴, which is secured to the circular disk E, passes.

Eccentrically mounted on and keyed to the 15 tube D at about midway of its length are two similar circular disks H and K, which are not in exact vertical arrangement, as is shown in Figs. 1, 10, and 11, and each of these disks H and K is provided with an annular groove, in 20 which is mounted a ring h, which is adapted to turn thereon. The rings h are preferably composed of two parts connected, as shown in Fig. 12, and connected with the ring h on the disk H is an arm h², which is curved outwardly and upwardly, as shown in Figs. 1 and 25 11, and connected with the ring h on the disk k is a similarly-curved arm h³, which is of the same length as the arm h².

Passing vertically through the horizontal ex- 30 tension g^3 of the arm g and the end of the arm E⁴ and movable therein is a double-crank shaft M, which is provided at its upper end with a segmentally-curved arm m, with which a globe m² is connected. The globe m² repre- 35 sents the earth and is connected with the arm m in the usual or any preferred manner, and the lower end of the double-crank shaft M is provided with an inwardly-directed crank m³, with which the arm h² of the disk H is 40 revolubly connected, and the arm h³ of the disk K is pivotally connected with the lower arm of said double-crank shaft at m⁴, and the said lower arm of said double-crank shaft is about twice the length of the upper arm there- 45 of, as shown in Figs. 1 and 11.

The operation will be readily understood from the foregoing description when taken in connection with the accompanying drawings.

In the plan view shown in Fig. 2 the ball- 50 bearings a⁶ around the perimeter of the countersunk top a⁴ of the elliptical casing a² are omitted, and in the operation of the device, as hereinafter described, the elliptically-mount- 55 ed circular disk E moves around the tube D, and the perimeter thereof bears on the ball- 60 bearings a⁶, which are held in place by the annular rim or flange formed by the top of the elliptical casing a² and the groove a⁵, in which said bearings are placed. The globe 65 m² may be moved entirely around the globe F by taking hold of the arm g and swinging it around on the top of the tube D. In this operation the arm E⁴, which is connected with the disk E, and the arms h² and h³, which are 70 connected with the eccentrically-mounted disks H and K, together with the rings h on said disks, are also carried around the tube

D, and the shaft M is turned. In this operation the tube D is also moved transversely through the elliptical opening a⁷ in the countersunk top of the elliptical casing a², this movement of said tube being occasioned by the disk E, which is eccentrically and movably mounted on said tube and which as it is carried around said tube by the arm E⁴ 75 moves said tube laterally, as above described. The distance between the globe F and the globe m² will thus increase and decrease as the arm g is revolved, and no matter in what position the arms h² and h³ may be the axis 80 of the globe m² will always be held in the same relative position with reference to the globe F, said axis being represented in two different positions by the dotted lines m⁵ in Fig. 10. It will be understood that while the shaft 85 M is turned the distance therefrom of the tube D never varies, the distance between the globes F and m² being changed by reason of the transverse movement of the tube D, which is occasioned by the disk E, which is revolu- 90 bly mounted thereon and which is carried around by the movement of the arm E⁴, which is also carried around by the movement of the arm g, as hereinbefore described. It will also be understood that this lateral movement 95 of the globe m² is not very great, being only equal to the inner diameter of the tube D; but said movement is sufficient for the purpose for which it is designed.

In Fig. 4 the disk E is shown in its central 100 position, in which it bears upon the ball-bearings a⁶ at the opposite sides of the elliptical casing a², but as said disk E is carried around said casing, as hereinbefore described, it will be apparent that it will bear on the said ball- 105 bearings at each end of said casing, and the ball-bearings b² and d³ facilitate the trans- verse movement of the tube D and reduce the friction of the base-plate d with which said tube D is connected.

By means of this device the movement of the earth through its orbit or around the sun and the relative positions of these bodies during the year may be clearly demonstrated.

This device is simple in construction and 115 operation and perfectly adapted to accomplish the result for which it is intended and is also comparatively inexpensive, and it will be apparent that changes in and modifications of the construction herein described may be 120 made without departing from the spirit of my invention.

Having fully described my invention, I claim as new and desire to secure by Letters Patent—

1. In a tellurian, a base-plate, an elliptical casing mounted thereon and provided with a countersunk top in which is formed a trans- 125 verse elliptical opening, a stationary shaft which passes upwardly centrally through said opening, a laterally-movable tube mounted in said opening through which said shaft passes, a disk eccentrically and movably mounted on said tube above the countersunk bottom of

5 said casing, a globe mounted on the upper end of said stationary shaft, a revolute arm mounted on the upper end of said tube and provided at its outer end with a vertical portion having a horizontal extension, a curved arm connected with said disk and with said revolute arm, a vertical shaft mounted in the end of said curved arm and in the horizontal extension of said revolute arm, said 10 shaft being provided in its upper end with a segmental portion with which a globe is connected, and at its lower end with a crank, and two disks eccentrically keyed to said tube, each of which is provided with a ring 15 which is revolutely mounted thereon, similar curved arms connected with each of said rings and the free ends of which are connected with said crank, substantially as described.

2. In a tellurian, a base-plate, an elliptical 20 casing mounted thereon and provided with a countersunk top in which is formed a transverse elliptical opening, and around which is placed an elliptical row of ball-bearings, a shaft-plate mounted in said casing, and provided with a vertical shaft which passes centrally through said opening, a transversely-movable tube mounted in said transverse elliptical opening and through which said shaft passes, said tube being provided at its 25 lower end with a base-plate between which and the shaft-plate ball-bearings are placed, a disk eccentrically and revolutely mounted on said tube above the countersunk bottom of said casing, and provided with a curved arm, 30 a globe mounted on the upper end of said shaft, a revolute arm mounted on the upper end of said tube with which said curved arm is connected, a vertical shaft supported by said curved and said revolute arm, a globe connected with the upper end thereof, said vertical shaft being also provided at its lower end with a crank, two disks eccentrically keyed to 35 said tube, revolute rings mounted thereon, and arms connected with said rings and with said crank, substantially as described.

4. A tellurian, comprising a base-plate, upright arms connected therewith, an annular plate connected with said arms, an elliptical casing mounted on said base-plate and provided with a top in which is formed a transverse elliptical opening, a stationary shaft passing vertically through said opening, a transversely-movable vertical tube mounted in said opening through which said shaft 50 passes, a globe connected with the upper end of said shaft, a revolute arm mounted on the upper end of said tube, a globe supported by a shaft which passes through the end of said revolute arm, and means for operating said

transversely-movable tube, substantially as 60 described.

4. A tellurian, comprising a base, an annular plate supported thereover, an elliptical casing supported on said base and provided with a top in which is formed a transverse 65 elliptical opening, a vertical stationary shaft mounted centrally in said opening, a laterally-movable tube which is mounted in said opening, and through which said shaft passes, a globe mounted in the upper end of said stationary shaft, a revolute arm mounted on the upper end of said tube, a disk eccentrically mounted on said tube, a curved arm connected with said disk and with said revolute arm, a vertical shaft supported by said arms, 70 the lower end of which is provided with a crank, two disks eccentrically keyed to said tube each of which is provided with a revolute ring, arms connected with each of said rings and with said crank, and a globe mounted on the upper end of said last-named shaft, 75 substantially as described.

5. A tellurian, comprising a base, an annular plate supported thereon, divided into twelve spaces, an elliptical casing mounted 85 on said base and provided with a countersunk top in which is formed a transverse elliptical opening, said top being also provided around its perimeter with ball-bearings, a shaft provided with a base-plate which is mounted in 90 said elliptical casing, said shaft being projected upwardly centrally through said opening, a laterally-movable tube mounted in said opening and through which said shaft passes, and the lower end of which is provided with 95 a base-plate, ball-bearings between the base-plate of said shaft and the base-plate of said tube, a disk eccentrically mounted on said tube above the countersunk bottom of said casing, a globe connected with the upper end 100 of said stationary shaft, a revolute arm mounted on the upper end of said tube, a curved arm connected with said disk and said revolute arm, a vertical globe-shaft mounted in the outer ends of said arms, and provided 105 at its lower end with a crank, and two disks eccentrically keyed to said tube, each of which is provided with a revolute ring, and arms connected with said rings and with said crank, 110 substantially as described.

In testimony that I claim the foregoing as my invention I have signed my name, in presence of the subscribing witnesses, this 2d day of April, 1898.

DANIEL THOMAS WILLIAMS.
